CARL A. FLOOD AND JOHN H. GIBBS, OF FRAMINGHAM, MASSACHUSETTS, ASSIGNEES
TO DENNISON MANUFACTURING COMPANY, OF FRAMINGHAM, MASSACHUSETTS,
A CORPORATION OF MASSACHUSETTS.

PAPER ARTICLE METHOD AND APPARATUS.

Application filed August 9, 1926. Serial No. 128,078.

The object of the present invention is to provide paper articles such as napkins, doilies, tablecloths, streamers, festoons and the like having torn edges which if desired may be colored, and an improved method and apparatus for making such articles. For the purpose of illustration a concrete embodiment of the invention is shown in the accompanying drawings, in which:

10 Fig. 1 is a diagrammatic view of the apparatus:

Fig. 2 is an end view of the tearing mechanism:

15 Fig. 3 is a top view of the two lower rolls shown in Fig. 2:

Fig. 4 is an elevation of the tearing mechanism viewed from the left of Fig. 2:

20 Fig. 5 is a detail section on line 5—5 of Fig. 4, showing the parts in a position slightly advanced beyond the position shown in Fig. 4:

Fig. 6 represents paper napkins made according to the present invention; and

25 Figs. 7 and 8 show different types of rolls for wetting the paper.

As illustrated in the drawings crepe paper C is fed from a roll 1 having a surface unwinding belt 2, over a roll 3, thence under a larger roll 4 where the paper is wet along 30 both transverse and longitudinal lines for the purpose of tearing the paper along these lines into napkins or other units at a later stage in the apparatus, thence over a large skeleton roll 5, thence between the lower roll 35 6 and upper rolls 7 and 8 where the paper is torn both transversely and longitudinally into units U, which are fed between upper and lower sets of guide belts 9 and 10 around the drying drum 11 and thence to any suitable receiver or conveyor, such as illustrated by the belt conveyor 12. A part or all of the rollers or drums, over which the paper passes, may be driven by any suitable driving means, it being understood that driving 40 45 rollers as spaced locations along the path of the paper should be synchronized as by gearing the rolls together in well-known manner.

While passing under roll 4 the paper is wet along transverse and longitudinal lines 50 by means of one or more rolls such as shown at 13 and 14, these rolls having peripheral ridges which pick up the moisture from rolls 15 and 16 respectively, dipping in pans 17 and 18, and transmitting the liquid

55 to transverse and longitudinal lines on the paper where the ridges contact with the paper. One of the rolls 13 and 14 may have circumferential ridges, such as shown at 19 in Fig. 7, to wet the paper along longitudinal lines and the other of these two rolls 60 may have one or more longitudinal ridges, such as shown at 20 in Fig. 7, for wetting the paper along transverse lines; or one of the rolls 13 and 14 may have both circumferential and longitudinal ridges such as 65 illustrated in Fig. 7, in which case one of the two rolls may be dispensed with.

The liquid in pans 17 and 18 may be colored to color the edges of the torn paper articles and by employing two pans and associated rollers two colors may be applied to the edges of the articles. In this case each roll may be provided with both circumferential and longitudinal ridges 19' and 20' which are discontinuous as illustrated in 70 Fig. 8, in which case the two rolls 13 and 14 are so synchronized that one roll wets the paper in the spaces between the places where the other roll wets the paper, so that the two colors alternate along the edges of the 75 article both transversely and longitudinally of the sheet. Obviously other types of printing and coloring may be employed, including the printing of monograms or designs inside the margins of the paper 80 articles.

85 The skeleton roll 5 comprises end disks interconnected by rods 21 at their periphery so that the paper when passing over this roll contacts with the roll only along narrow 90 lines so as not to spread the liquid in the paper. If desired the rods 21 may be grooved on the outside at the places where the longitudinal lines of wetting occur so that these wet lines do not contact with the drum or roll at all. The rods 21 are preferably so spaced that the transverse lines of wetting fall between the rods, the distance between the transverse lines of wetting preferably being equal to the distance between 95 the rods 21.

As shown in the drawings the apparatus is intended to divide the paper C into three equal widths and to trim off the margins. After the paper passes over the skeleton 105 drum 5 the margins 22 of the paper are fed between two pairs of rolls respectively, one pair being shown at 23 in Fig. 1. The rolls

23 are driven in synchronism with the drum 5 so that the margins are torn off at the roll 24 by the pull of the rolls 23, the main portion of the paper continuing through the mechanism which divides the sheet longitudinally and transversely as will now be described.

The roll 6 has two longitudinal recesses 25 in its periphery and two relatively wide circumferential recesses 26 (Figs. 1 and 3) to accommodate the tearing blades 27 and 28 mounted on a common rotor. The blades 27 are in the form of disks extending into the groove 26, it being understood that the grooves and disks are spaced transversely of the sheet to correspond with the spacing of the ridges 19 on rolls 13 and 14 which wet the paper before it reaches the tearing mechanism. However, as indicated in Figs. 3 and 4, the longitudinal lines 28' along which the paper is wet preferably pass slightly to one side of the tearing disks 27 so that the disks do not contact with the moist lines; consequently when using coloring matter it does not contact with the disks and therefore does not smear when the paper is torn. Inasmuch as the disks 27 extend into the grooves 26 across the plane of the paper the paper is torn along the longitudinal moist lines 28' by the disk 27. The paper is torn along the transverse lines of wetting by the blades 28 passing into the grooves 25 as illustrated in Fig. 5, it being understood that the circumferential distance between the grooves 25 is approximately equal to the distance between the transverse lines of wetting on the paper. However, the transverse lines of wetting 29 (Fig. 3) preferably come slightly in the rear of the line of contact between the paper and the blade 28 so that the blade does not contact with the moist line. The blade 28 is divided into sections to accommodate the disks 27 as shown in Fig. 4. The blade 28 is also recessed as shown at 30 so as not to contact with the longitudinal lines along which the paper is wet. The blade 28 is also provided with recesses 31 to accommodate the belts hereinafter described. The rolls 7 and 8 are provided with longitudinal grooves 32 and circumferential grooves 40 to avoid contact with that part of the paper which is wet.

After the paper is torn longitudinally and transversely into small units U as above described it passes between the belts 9 and 10 thence over the heating drum 11, which is heated in any suitable manner, and thence to the conveyor 12, the belts 9 and 10 and the conveyor belts 12 traveling in the direction indicated by the arrows.

In order to insure uniform feed of the paper articles between the belts 9 and 10 after they are separated by the tearing mechanism as above described, blades 33 are mounted on the shaft 34 to extend into nar-

row grooves 35 in the roll 6 as illustrated in Figs. 2 and 3. At each end of the shaft 34 a single blade is mounted on a hub 36 and between each pair of belts two blades are mounted on a single hub 37, 37', 37'' etc. (Fig. 3). In the spaces between these hubs belt pulleys 38 are mounted to rotate on the shaft 34.

As shown in Fig. 4 the roll 7 is provided with peripheral grooves 39 the depth of 75 which is approximately equal to the thickness of the belts 9, whereby the outer surfaces of the belts in these grooves are approximately flush with the periphery of the rolls 7 so that the paper C is not deformed 80 by the belts 9 as the paper passes under the roll 7.

From the foregoing it will be evident that paper may be divided longitudinally and transversely into units of any desired size, 85 that the operation is continuous and automatic, that the edges of the units may be colored with one or more colors, and that after the paper is moist by the rolls 13 and 14 the moistened lines do not contact with 90 any part of the apparatus until the paper reach the belts 9 and 10. Inasmuch as these belts are continuously dried by the dryer 11 they do not tend to smear the coloring matter.

As shown in Fig. 6 the crepe paper napkin 40, which is illustrative of the many articles adapted to be made according to this invention, has its torn edges colored alternately with two colors 41 and 42 confined 100 substantially to the width of the margin of irregularities in the torn edges.

The paper article resulting from the method and apparatus claimed in this application are claimed in copending application Serial No. 147,152 filed November 8, 1926, which is a division of this application.

We claim:

1. Apparatus for forming articles from sheet paper comprising means for feeding an elongate sheet of paper lengthwise along a predetermined path, means for wetting the paper along lines respectively extending transversely and longitudinally of the sheet while in transit along said path, and means 115 farther along said path for subsequently tearing the paper along said lines to form paper articles.

2. Apparatus for forming articles from sheet paper comprising means for feeding an elongate sheet of paper lengthwise along a predetermined path, a roll having longitudinal and circumferential flanges for wetting the paper along lines respectively extending transversely and longitudinally 120 of the sheet while in transit along said path, and means farther along said path for subsequently tearing the paper along said lines to form paper articles.

3. Apparatus for forming articles from 130

sheet paper comprising means for feeding an elongate sheet of paper lengthwise along a predetermined path, means for wetting the paper along lines respectively extending transversely and longitudinally of the sheet while in transit along said path, means for tearing off the margins of the elongate sheet along certain of said longitudinal lines, and means for tearing the sheet along said transverse lines and other of said longitudinal lines to divide the sheet both transversely and longitudinally.

4. Apparatus for forming articles from sheet paper comprising means for feeding an elongate sheet of paper lengthwise along a predetermined path, means for wetting the paper along lines respectively extending transversely and longitudinally of the sheet while in transit along said path, means for tearing off the margins of the elongate sheet along certain of said longitudinal lines, and means farther along said path, for tearing the sheet along said transverse lines and other of said longitudinal lines to divide the sheet both transversely and longitudinally.

5. Apparatus for forming articles from sheet paper comprising means for feeding an elongate sheet of paper lengthwise along a predetermined path, means for wetting the paper along lines respectively extending transversely and longitudinally of the sheet while in transit along said path, and means farther along said path for subsequently tearing the paper along said lines to form paper articles, said last means including a roller having longitudinal and circumferential grooves and a juxtaposed rotor having longitudinal and circumferential blades ar-

ranged to project into said grooves as the parts rotate in synchronism.

6. The method of forming articles from sheet paper which comprises feeding an elongate sheet of paper lengthwise along a predetermined path, wetting the paper along lines respectively extending transversely and longitudinally of its length while in transit along said path and subjecting the paper to tension in the regions of the wet lines, thereby to tear the sheet transversely and longitudinally into units.

7. The method of forming articles from sheet paper which comprises feeding an elongate sheet of paper lengthwise along a predetermined path, wetting the paper with a dye solution along lines respectively extending transversely and longitudinally of its length while in transit along said path, and subsequently tearing the paper along said lines to form articles whose torn edges are colored.

8. The method of forming articles from sheet paper which comprises feeding an elongate sheet of paper lengthwise along a predetermined path, wetting the paper along lines respectively extending transversely and longitudinally of its length while in transit along said path, the paper being wet with different dye solutions applied alternately along said lines, and subsequently tearing the paper along said lines to form articles whose torn edges are colored with alternating colors.

Signed by us at Framingham, Massachusetts, this second day of August, 1926.
